(57) **CLAIM**

We claim the ornamental design for an electronic device, as shown and described.

DESCRIPTION

FIG. 1 is a front perspective view of an electronic device showing our new design according to a first embodiment; FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front view of an electronic device showing our new design according to a second embodiment;

FIG. 10 is a front view of an electronic device showing our new design according to a third embodiment;

FIG. 11 is a front view of an electronic device showing our new design according to a fourth embodiment;

FIG. 12 is a front view of an electronic device showing our new design according to a fifth embodiment;

FIG. 13 is a front view of an electronic device showing our new design according to a sixth embodiment;

FIG. 14 is a front view of an electronic device showing our new design according to a seventh embodiment;

FIG. 15 is a front view of an electronic device showing our new design according to an eighth embodiment;

FIG. 16 is a front view of an electronic device showing our new design according to a ninth embodiment; and,

FIG. 17 is a front view of an electronic device showing our new design according to a tenth embodiment.

The broken lines in the figures depict portions of the electronic device which form no part of the claimed design. The dot-dash broken lines in the figures represent a boundary of the claimed design and form no part thereof.

The rear, left-side, right-side, top, bottom and rear perspective views of the second through tenth embodiments of the electronic device depicted in FIGS. 9 through 17 have been
